UNITED STATES PATENT OFFICE.

MARTIN R. DRISCOLL, OF FRISCO, UTAH.

SCREEN FOR STAMP-MILLS.

SPECIFICATION forming part of Letters Patent No. 629,242, dated July 18, 1899.

Application filed January 12, 1899. Serial No. 701,955. (No model.)

To all whom it may concern:

Be it known that I, MARTIN RICHARD DRISCOLL, of Frisco, in the county of Beaver and State of Utah, have invented a new and Improved Screen for Stamp-Mills, of which the following is a full, clear, and exact description.

The object of the invention is to provide a new and improved screen for stamp-mills which is simple and durable in construction, arranged to permit a convenient and quick change of the worn-out screen-cloth without stopping the battery, and at the same time prevent coarse ore from passing to the pulp-conveyers and amalgamating-plates or other devices for treating the pulp.

The invention consists of novel features and parts and combinations of the same, as will be fully described hereinafter and then pointed out in the claims.

A practical embodiment of my invention is represented in the accompanying drawings, forming a part of this specification, in which similar characters of reference indicate corresponding parts in all the views.

Figure 1 is a front elevation of the improvement. Fig. 2 is a transverse section of the same on the line 2 2 in Fig. 1. Fig. 3 is a sectional plan view of the same on the line 3 3 in Fig. 1. Fig. 4 is a similar view of the same on the line 4 4 in Fig. 1. Fig. 5 is a rear face view of the improvement, and Fig. 6 is a transverse section of the same on the line 6 6 in Fig. 1.

On the front A of the stamp-mill frame is arranged an outlet-opening A', adapted to be covered by one or more screen-cloths for screening the pulp as it passes from the stamp-mill to the pulp-conveyers, amalgamating-plates, or other devices employed for treating the pulp in the usual manner, the screen-cloth serving to retain the coarser pulp in the mill until it is reduced to the desired mesh. As illustrated in the drawings, two screen-cloths are employed, and in order to hold the screen-cloth in place and to permit of quickly removing the worn-out portions of the screen-cloth without stopping the battery I provide the following construction.

On the face of the front A is arranged a recess adjacent to the opening A' to receive a skeleton frame provided with vertical mem-

bers B B' B² and a bottom member B³ for connecting the vertical members with each other. The middle vertical member B² is 55 adapted to be fastened to the front A, near the upper end thereof, by a suitable bolt C, as is plainly indicated in Figs. 1 and 6. On the front face of the skeleton frame is riveted or otherwise secured a U-shaped frame 60 D, and on the back of the skeleton frame is riveted a frame similar in shape to the skeleton frame and comprising vertical members E E' E² and a base member E³. (See Fig. 5.) The last-mentioned frame fits with its side 65 members into the opening A' in the front of the stamp-mill frame, as is plainly indicated in Figs. 3, 4, and 6, the vertical members terminating a suitable distance below the top of the opening. 70

Near the upper ends of the vertical members B B' B² of the skeleton frame and at the front face thereof are arranged brackets F for carrying reels F', supporting rolls G G' of screen-cloth G² G³, adapted to be stretched 75 downward over the openings between the vertical members B B' and B² B' of the skeleton frame. The stretched portions of the screen-cloth G² G³ are secured in position at their sides and lower ends by U-shaped clamping-frames H H', respectively, engaged by bolts 80 I, projecting from and carried by the vertical members of the skeleton frame, each bolt being preferably provided with a wing-nut to permit the operator to conveniently screw up 85 or unscrew the nut to press the frame in engagement with the sides and bottom portions of the corresponding screen-cloth. The bolts I engage elongated notches H² in the side members of the clamping-frames H H', so that when 90 the nuts of the bolts I are loosened then the clamping-frames can be shifted upward, as indicated at the left in Fig. 1, when it is desired to remove the lower worn-out portion of the screen-cloth, as hereinafter more fully 95 described.

The extreme lower portions of the screen-cloth G² and G³ are drawn between the bottom members of the clamping-frames H H' and the bottom member B³ of the skeleton 100 frame, to be then clamped in position on the front of the bottom members of the clamping-frames H H' by bars J J', each held on bolts K, carried by the bottom member of the frame

D, the bolts having wing-nuts abutting against spring-washers K' to firmly press the bars J J' against that portion of the screen-cloth folded upon the front of the bottom members 5 of the clamping-frames H H'.

In the openings formed between the vertical members of the skeleton frame extend gates L, each provided near its upper end with handles L' to permit the operator to slide the 10 gates upward or downward and expose more or less screen-cloth to the inside of the stamp-mill, as will be readily understood by reference to Fig. 2. The side edges of each gate L fit against the inner edges of the vertical members B B² and B² B', and in order to permit a convenient sliding of the gate in an upward or downward direction the gate after adjustment is secured in place by a bolt N, carried by the front A of the stamp-mill frame, 15 said bolt extending through a vertically-disposed slot L² in the gates and covered at its lower portion by a plate O, hung on the bolt N. It is understood that each gate extends directly in the rear of the corresponding screen-cloth G² G³, and when the gate is moved into a lowermost position it completely closes that 20 portion of the skeleton-frame opening to prevent the pulp from passing from the stamp-mill to the screen-cloth. The gate is moved 25 down into a closed position when it is desired to remove a worn-out lower portion of a screen-cloth, it being understood that in this case the gate is lowered and then the clamping-frames H or H' are loosened and likewise the 30 bars J or J'. The operator is then enabled to pull on the lower end of the screen-cloth, so 35 as to unwind the latter from the corresponding reel, and when the desired amount of screen-cloth has been unwound and drawn 40 through between the lower members of the clamping-frames and the clamping-bars J or J' then the operator cuts off the worn-out portion and folds up the lower end of the cloth upon the front lower member of the clamping-frame. The latter is now lowered to its 45 former position, and the nuts on the bolts I are screwed up to fasten the clamping-plates in position, and then the clamping-bars J or J' are screwed down upon the end of the 50 screen-cloth extending over the front of the lower member of the clamping-frame. When this has been done, the operator can again 55 raise the corresponding gate, so as to permit the pulp to pass from the interior of the stamp-mill screen through the meshes of the screen-cloth to the apparatus for further treatment.

In order to bring the gates L into the proper position to prevent leakage of the pulp 60 through the device at the time the gate is in a lowermost position, I provide each gate at its rear face with a doubled-up or reinforced portion L³, adapted to slide in vertically-disposed and slightly-inclined guideways P, secured to the bottom member E³ of the reinforcing-frame. Now it is evident that when 65 a gate L is lowered it passes into the guide-

ways P, and as the faces thereof are inclined the gates are pressed forward with the upturned portions L³ against the vertical members E E' E², so as to completely close the skeleton frame by the gates.

It is understood that the side edges of the screen-cloth G² and G³ extend slightly upon the vertical members B B² B' of the skeleton frame to be clamped in position thereon by the side members of the clamping-frames H H', so as to securely hold the screen-cloth in place, the lower portion thereof being held in place by the bottom members of the clamping-frames H H' and the clamping-bars J J' in the manner above explained.

From the foregoing it is evident that by loosening the clamping-frames and clamping-bars the operator is enabled to readily loosen the screen-cloth and draw the same downward through the skeleton frame to bring an unused portion of the cloth into the opening covered by the corresponding gate. The portion projecting below the bottom member of the clamping-frame and folded back upon the front thereof is taken hold of by the operator to conveniently draw the screen-cloth downward as said portion of the screen-cloth forms a convenient hold.

It will be seen by the arrangement described that it is not necessary to stop the battery or take out the entire frame while changing the screen-cloth to remove a worn-out portion and replace it by a new unused cloth, and consequently considerable labor is saved, and there is no danger of large particles passing from the mill to the amalgamating-plates while the change is taking place. By having two screen-cloths, as described, the operator can change one for replacing worn-out portions while the other is in use, it being understood that the operator previously to making the change closes the corresponding gate L. When the screen-cloth has been changed, the operator again lifts the corresponding gate to the previous position to allow the pulp to pass through the new screen portion.

When it is desired to repair the stamp-mill, the skeleton frame with the parts carried thereby can be readily taken out of the front A of the mill to give ready access to the interior of the latter.

When new dies or shoes are required for the stamp-mill, then the height of discharge is readily regulated and increased by the operator raising the gates correspondingly, and when the dies or shoes have worn the gates are correspondingly lowered, as less material is now brought into a proper condition to be discharged through the screen-cloth within a given time.

When the battery requires new shoes or dies, ample room is afforded for putting such shoes in position by unclamping the screen-cloth and reeling the latter upon the reels and lifting the gates to give access to the stamp-mill by way of the screen-frames.

Having thus fully described my invention,

I claim as new and desire to secure by Letters Patent—

1. A stamp-mill, having an apertured frame, a roll of screen material mounted above the aperture and having a portion extending over the aperture, a clamping-frame extending about the lower and side edges of the aperture and covering the edge of the screen material, said frame having vertically-extending bolt-recesses in its side bars, clamping bolts within said recesses and an auxiliary clamping-bar engaging the outer face of the lower side of the clamping-frame, substantially as described.
- 15 2. A stamp-mill, having an apertured frame, a roll of screen material mounted above the aperture and having a portion extending over the aperture, a clamping-frame extending about the lower and side edges of the aperture and covering the edges of the screen material, means for releasably securing the members of the clamping-frame and the screen beneath it to the screen-frame, and an auxiliary

clamping-bar engaging the outer face of the lower side of the clamping-frame, substantially as described.

3. A stamp-mill, having an apertured mortar, a roll of screen material mounted above the aperture and having a portion extending over the aperture, a clamping-frame extending about the lower and side edges of the aperture and covering the edges of the screen material, means for releasably securing the members of the clamping-frame and the screen beneath it to the screen-frame, an auxiliary clamping-bar engaging the outer face of the lower side of the clamping-frame, a gate mounted to slide vertically at the rear of the screen, and inclined guides engaging the lower edge of the gate to force it laterally to its seat as it reaches its lowermost position, substantially as described.
